DESIGN FOR A DECORATIVE ENSEMBLE FOR USE ON A CHRISTMAS TREE OR THE LIKE

Abraham Damast and Murray Damast,
New York, N. Y.

Application April 29, 1942, Serial No. 106,745

Term of patent 14 years

To all whom it may concern:

Be it known that we, Abraham Damast and Murray Damast, citizens of the United States of America, residing in the city of New York and State of New York, have invented a new, original, and ornamental Design for a Decorative Ensemble for use on a Christmas Tree or the like, of which the following is a specification, reference being had to the accompanying drawing, forming part thereof, wherein,

Figure 1 is a front elevational view of a deco-

rative ensemble for use on a Christmas tree or the like, showing my new design, and

Figure 2 is a side elevational view thereof.

The rear of the design is substantially the same in appearance as the front.

We claim:

The ornamental design for a decorative ensemble for use on a Christmas tree or the like, substantially as shown, and described.
